UNITED STATES PATENT OFFICE

SYDNEY A. CAMPBELL, OF BRIGHTON, AND LOTHAIR I. VAN BUSKIRK, OF NEWTON-
VILLE, MASSACHUSETTS

TOY HANDKERCHIEF CASE AND PURSE

Application filed October 10, 1928. Serial No. 311,641.

This invention relates to improvements in children's novelty handkerchief cases and/or purses and the general object of the invention is to provide a device of this character which may be attractive to children, and provide a toy as well as a purse or handkerchief case of utility. A further object of the invention is to provide a device of this character which will simulate a child's pet such as an animal, bird, fish or flower or a building.

Preferably the handkerchief case or purse is formed of soft flexible sheet material comprising a front section shaped to simulate the child's pet, and a back section of similar construction secured thereto at or near its peripheral edge to form a space therebetween with a cut or slot preferably in the back section extending preferably transversely thereof to provide access to the space therebetween.

In the manufacture of such articles there are many matters to be considered such as the appearance, the durability and the cost of production. The appearance of the finished product must be such as to attract the attention of small children. The article must be staunch enough to withstand the rough handling to which children are prone to subject it. It must also be possible to manufacture the article on an extended scale at a minimum of cost. Among the chief objects of this invention are to provide an article which will combine all the desirable qualities above suggested.

A further object of the invention is to provide an article which may be used to display and sell in combination with other articles such as handkerchiefs and the like.

A further object of the invention is to provide a fastening device for securing the lower portion of the back section to the front section to retain objects placed in the pocket formed between the front and back sections. Another object of the invention is to provide a tab upon the back section by means of which

the fastening device can be readily detached.

These and other objects and features will more fully appear from the following description in connection with the accompanying drawings, and will be particularly pointed out in the claims.

Preferred embodiments are illustrated in the accompanying drawing in which:

Fig. 1 is a front elevation of the handkerchief case.

Fig. 2 is a rear elevation of the same.

Fig. 3 is a front elevation of the handkerchief case illustrating another form which the device may take.

Fig. 4 is a cross-sectional view on line 4—4 of Fig. 1.

The illustrated embodiments of the invention shown in the accompanying drawings comprise a purse or handkerchief case formed of preferably flexible sheet material having a front section shaped to simulate a child's pet, a complementary back section secured thereto at or near its peripheral edge to form a space therebetween, and a cut or slot in the back section extending transversely thereof to provide access to the space therebetween.

The article as herein shown preferably is made of felted sheet material. It will be understood however that any material may be used such as soft leather, woven fabric, sheet rubber etc. As illustrated in Fig. 1 the handkerchief case or purse comprises a front section 1 of felt cut out to represent a dog. Another section of felt 2 is cut to the exact shape of the front section and secured thereto by a line of stitching 3 near the peripheral edge thereof. The front section has drawn or imprinted or otherwise displayed thereon the features and limbs of the dog and any ornamentation which may be desired.

It will be noted that since the back and front sections 1 and 2 are complementary it is necessary to provide a single die only to cut them from the material. Furthermore, several sections may be cut simultaneously by

superimposing several sheets of the material thus reducing the time required to cut out the sections.

The back section 1 as illustrated in Fig. 2 has a cut 4 therein which extends substantially horizontally the width of the section, and is shaped at or near its center to form a tab 5 which is grasped by the fingers to separate that portion of the back section 2 below the cut 4 from the front section in order to provide access to the space there is between the front and back sections. This space is used as a compartment to carry money, handkerchiefs or any other articles it is desired to have about the person. Obviously the slit to provide access to the compartment may be made in the front section as well as the back section.

In order to prevent loss of the articles carried by the handkerchief case, means are provided to close the opening formed by the cut 4. Any suitable means may be employed, and as herein shown a snap fastener 7 is provided. One member 8 of the fastener 7 is fixed into the front section 1 adjacent to cut 4 and slightly below it while the other member 9 of the fastener is situated directly in back of the section 8 so that the two sections register and may be fastened by a simple pressure of the fingers.

When it is desired to gain access to the handkerchief case it is merely necessary to pull the sections apart by means of the tab 5. While the cut in the back section may be of any shape one desirable form is herein shown in Figure 2 in which the portion of the cut to either side of the tab 5 when viewed from above has a concave curvature. Such construction is ornamental and avoids the possibility of tearing the fabric at the extremities of the cut 4.

By placing the snap fastener centrally of the transverse cut and extending the cut or slit well toward the edges of the back section sufficient space in the cut is provided to permit a folded handkerchief to be placed in the space between the front and back sections with the corners of the handkerchief extending through the cut or slot sufficiently to project beyond the edges of the purse so that the corners of the handkerchief will in effect simulate wings projecting from the sides of the cut. The snap fastener which secures the front and rear sections together will hold the handkerchief from displacement thereby performing the double function of securing the wings in place and preventing the loss of the handkerchief which otherwise might slip out of the pocket during the handling of the purse.

A suitable carrying device is provided which consists of a loop 10 of the same material out of which the body of the case is made. The free ends of the loop are inserted between the front and back sections at the uppermost

point of the figure, and are held in place by the same line of stitching that secures the back and front sections. This is the preferred form of carrying device, but it will be understood that any form of carrying device may be used within the scope of the claims.

The device thus constructed provides an attractive toy and also a convenient form of purse to receive the handkerchief, money or any of the numerous child's treasures. A preferably cheap embodiment of the device may be made by securing to a front sheet simulating an animal or another pet a patch pocket having a snap fastener and a suitable tab of the character above described. The device may be conveniently carried either by the hand or on the child's wrist. By reason of the soft and flexible character of the device, injury to the child is avoided, and a suitable toy provided which the child may take to bed with its other pets.

To illustrate the variety of forms which the device may take a purse made up to simulate a rabbit is shown in Fig. 3. Like parts therein are indicated by like characters as set forth in the other illustrated forms. Obviously the device may be constructed in other forms such as a lamb, bear, bird, fish or a building, or other children's pets within the spirit and scope of the following claims.

Having thus described the invention, what is claimed as new, and desired to be secured by Letters Patent, is:

1. A toy handkerchief case and purse comprising a front section of flexible sheet material shaped to simulate a child's pet, a complementary back section of similar material secured thereto at or near its peripheral edge to form a space therebetween, said back section having a slit therein to provide access to said space, and complementary means carried by said front and back sections for retaining articles in said space.

2. A toy handkerchief case and purse comprising a front section of flexible sheet material shaped to simulate a pet animal, a complementary back section of similar material secured thereto at or near its peripheral edge to form a body portion having a space between the sections said back section having a slit therein extending substantially the width thereof, and a tab upon the lower flap formed by said slit with which to separate the portion of the back section below the cut from the front section thereby to provide ready access to said space.

3. A toy handkerchief case and purse comprising a front section shaped to simulate a pet animal, a complementary back section of similar material secured thereto at or near its peripheral edge to form a space therebetween, said back section having a slit therein, a detachable fastener situated adjacent to and below the slit, whereby the front and back sections may be fastened together to close

the opening formed by said slit, and a tab
secured by a member of said detachable fas-
tener to said back section by means of which
the fastener members may be released and the
lower portion of the back section separated
5 from the front to permit access to the space
therebetween.

In testimony whereof, we have signed our
names to this specification.

10 SYDNEY A. CAMPBELL.
LOTHAIR I. VAN BUSKIRK.
